INVENTOR:

W. B. H. Dowse

UNITED STATES PATENT OFFICE.

WILLIAM B. H. DOWSE, OF NEWTON, MASSACHUSETTS.

FASTENER.

SPECIFICATION forming part of Letters Patent No. 884,242, dated December 18, 1900.

Application filed January 18, 1900. Serial No. 1,951. (No model.)

To all whom it may concern:

Be it known that I, WILLIAM B. H. DOWSE, a citizen of the United States, residing at Newton, in the county of Middlesex and Commonwealth of Massachusetts, have invented 5 a new and useful Improvement in Fasteners, of which the following is a full specification.

My invention relates to and consists of an improved fastening for articles of wearing-apparel in which there is what is termed a "male" member and a "female" member, hereinafter described in detail, reference being had to the accompanying drawings.

My invention relates to that class of separable fasteners wherein either the socket or female member or the stud or male member is resilient.

My invention relates especially to the socket or female member. The female member of a separable fastener has hitherto been shown with the cap or cover of the female part as entirely independent of the article to which it is attached. These caps or tops have been made of material with various and elaborate designs, and finishes of various kinds have been put upon the top. Tops have been made in the factory in which the fasteners are made, with leather, celluloid, silk, or other material, and in various classes of trade a great deal of care is demanded to have the top correspond in finish and shade with the article to which it is to be attached. In my improved female member I am able to utilize the article itself to which the top is to be attached in forming the cover of the top or cap, and thus get the shade or top in harmony with the article upon which it is to be used.

Referring to the accompanying drawings, Figure 1 is an elevation showing my improved socket or female member. Fig. 2 is a vertical section of the same with the parts in position upon the material before they are set. Fig. 3 is a vertical section of my improved socket or female member as it appears when finally set upon the article to which it is to be attached. Fig. 4 is a solid stud member, and Fig. 5 a resilient stud member.

It is obvious that if the female member is non-resilient it is preferable to have the stud resilient, and vice versa.

In the accompanying drawings, Fig. 1 shows my improved female member, consist-

ing of three parts—the ring A, the material B, and socket-case C. The socket-case C may be either resilient or non-resilient. I 55 preferably form a rolled-in neck e on the socket-case C.

In Fig. 2 I have shown my improved female member placed upon the material to which it is to be attached and ready to be set permanently by the method and machine which are used for this purpose, a description of which will be set forth in another application for United States Letters Patent.

It will be noticed that the socket-case C is placed on the under side of the material and that the ring A is placed on the upper side of the material and forced down toward the flange of the socket-case C, so that the material is held between the ring and socket-case and covers the socket-case.

In Fig. 3 it will be noticed that the socket-case has been forced downward and the upper part of it expanded slightly over ring A, so that there is a slight groove f in the socket-case. This setting and formation of my improved female member is accomplished by means of suitable dies pressing the ring and case together, so that the material B is spread smoothly over the top of the socket-case and held thereto by means of the ring A. In this way I form a socket or female member, wherein the top consists of the part of the article itself to which the female member is attached.

I claim—

1. The combination in the socket or female member of a separable fastener of a socket-case, a plain ring of less diameter than the crown of the case, and the material between the case and ring, the case lying wholly on one side of the material, and the ring on the other side of the material, substantially as described.

2. The combination in a socket member of a separable fastener of a case, a plain ring, and the material between the case and ring, the case being wholly on one side of the material and being expanded on the plain ring, which lies wholly on the other side of the material, substantially as described.

3. The combination in the socket member of a separable fastener of a case, a plain ring and imperforated material between the case and ring, the case lying on one side of the mate-

rial, and being expanded on the ring, which lies on the other side, substantially as described.

4. A fastener member which consists of a case having a neck, a plain ring, and flexible material between the case and ring, the ring confining the case and material and binding against the neck of the case through the material, substantially as shown and described.
5. A member for a spring - fastening for gloves and other articles, comprising a shell on the under or inner side of the body fabric

of the article, said shell being laterally expanded, and a ring, exterior to the body fabric and embracing the latter and the contracted or non-expanded portion of the shell, substantially as set forth.

In witness whereof I have hereunto set my hand.

WM. B. H. DOWSE.
